UNITED STATES PATENT OFFICE

EDGAR KENNETH FREEMAN, OF TRENTON, NEW JERSEY, ASSIGNOR TO CIRCLE F. MFG. CO., OF TRENTON, NEW JERSEY, A CORPORATION OF NEW JERSEY

SCREW-SHELL CONTACT FOR ELECTRICAL SOCKETS

Application filed March 22, 1927. Serial No. 177,350.

This invention relates to electrical lamp sockets or receptacles, and more particularly to novel and practical means for gripping the plug of the lamp so that it will not be accidentally displaced.

To that end the invention contemplates a simple and practical screw shell construction which uniformly grips the plug of the lamp over its entire contacting surface, thereby affording added security against accidental displacement and yet at the same time permitting of the plug of the lamp being easily inserted and removed when desired. While various expedients have been heretofore resorted to for gripping the plug of the lamp, nevertheless where the gripping means utilized the screw shell contact as a part of such means, it has been customary to grip the lamp in a restricted zone or at one point only. Also in some constructions employing a spring for holding the lamp base in the screw shell, a depression or indentation is made in the lamp base and this frequently proves to be a detriment since it makes it difficult to remove the plug. With the present construction and arrangement however, these objections are overcome.

A further object of the invention is to provide a construction which may be easily manufactured and assembled, and which is inexpensive to make and reliable in use.

With the above and other objects in view which will more readily appear as the nature of the invention is better understood, the same consists in the novel construction, combination and arrangement of parts herein-after more fully described, illustrated and claimed.

A preferred embodiment of the invention is shown in the accompanying drawings, in which

Fig. 1 is a view of an electrical receptacle, partly in section, illustrating the present improvements.

Fig. 2 is a bottom plan view of the receptacle shown in Fig. 1.

Fig. 3 is an enlarged detail sectional view taken on the line 3—3 of Fig. 1, a lamp plug being shown in the screw shell member.

Fig. 4 is a detail perspective view of the

holding unit which includes the screw shell and tensioning spring.

Similar reference characters designate corresponding parts throughout the several figures of the drawings.

In carrying the present invention into effect it is particularly desired to avoid a construction wherein catches, pawls or other relatively fragile parts are used for maintaining a friction grip on the screw-threaded base or lamp plug. In other words, the invention aims to utilize the screw shell contact in such a way that the lamp plug or base may be screwed in for use in the usual way without obstruction or interference, and without contacting or engaging with anything but the screw shell contact itself until it reaches the usual center-plug contact.

Accordingly, as will be observed from the drawings it is proposed to utilize a screw shell designated generally as S having the flanges 1 at one end for connecting with the porcelain body B in the usual manner, and also having the opening 2 providing the necessary clearance for the center plug contact 3 of the receptacle.

The threaded portion 4 of the screw shell contact is provided with a plurality of longitudinally disposed spaced cuts or slits 5 which divide the entire circumference of the screw threaded portion 4 into a plurality of gripping fingers 6. These fingers are therefore distributed throughout the entire circumference of the screw shell and provide in effect a relatively expandable and contractible screw shell member under the influence of a coiled spring 7 which lies in the valleys of the threads or convolutions of the shell at the outside thereof.

The spring 7 is preferably helically wound and the normal diameter thereof is less than the normal diameter of the screw shell contact so that when the spring is applied to the outside of the screw shell contact all of the fingers 6 will be pressed inwardly thus providing a relatively constricted yielding threaded sleeve for receiving the lamp plug. The leading thread of the plug however, may be readily fitted into the initial receiving thread of the screw shell contact and the plug of

the lamp screwed into the shell against the frictional gripping action of the multiplicity of gripping elements. When the lamp plug is screwed home, it will be securely and effectively gripped throughout its length by the plurality of individual gripping fingers, and thereby effectually prevented from accidental rotation and consequent creeping of the socket.

10 From the foregoing it will be apparent that the primary object of the invention is to provide a screw shell contact having means for uniformly gripping the lamp plug over its entire contacting surface.

15 Many lamps become darkened due to the plugs creeping out of the screw shell contacts for a sufficient distance to permit the center plug of the lamp to move out of the center plug contact of the receptacle. The present 20 construction however prevents such an occurrence and maintains the lamp illuminated as long as the filament remains unbroken.

Without further description it is thought that the features and advantages of the invention 25 will be readily apparent to those skilled in the art, and it will of course be understood that changes in the form, proportion and minor details of construction may be resorted to, without departing from the spirit of 30 the invention and scope of the appended claim.

I claim:—

35 A screw shell contact for electrical receptacles consisting of the screw shell body formed with a spirally threaded portion having a plurality of slits disposed longitudinally of the shell body and opening through one end thereof, and a helical spring wire whose convolutions have the same spirality as 40 that of the threads of the shell body and whose normal diameter is less than the normal diameter of the screw shell body, the convolutions of the said spring wire lying in and following the valleys of the shell body threads at the 45 outside thereof.

In testimony whereof I hereunto affix my signature.

EDGAR KENNETH FREEMAN.
